PIANO CONSTRUCTION

Filed July 9, 1927

By His Attorney *LUMAN B. WING.*

Attorney
Philip B. Keh

UNITED STATES PATENT OFFICE

LUMAN B. WING, OF BROOKLYN, NEW YORK

PIANO CONSTRUCTION

Application filed July 9, 1927. Serial No. 204,500.

My invention relates to certain improvements in pianos which have their strings under the usual high tension, and more particularly to improvements in the structure and support of the piano plate mounted in operative relation with the sound-board.

Heretofore it has been customary to brace the opposite portions of the metal plate from which the piano strings are drawn under high tension in tuning the piano for use, by means of cross-bars which are superposed above the plate and sound-board thereby causing spaced-apart gaps in the bridges on which the piano strings bear. Such cross-bars are required to maintain the rigid structure of the piano plate under the enormous tension imparted to the piano strings but the breaks in the bridges occasion uneven tones derived from the strings adjacent the bridge gaps and supports due to the varying stresses and other causes so that it becomes increasingly difficult to keep the piano as a whole in proper tone.

The aim of my invention is, among other things, to provide an improved piano plate and sound-board assembly in which the bridges shall be continuous and uninterrupted by the gaps heretofore required for the brace bars, and this improvement is accomplished by placing such cross-bars and supports subjacent to the sound-board where such bars may hold the opposite portions of the piano plate in uniformly rigid relation. Further improved features and advantages of my invention will be apparent from the following detailed description thereof, and a preferred embodiment is illustrated in the drawings in which—

Fig. 1 is a top plan view of my improved piano plate structure.

Fig. 2 is an enlarged section taken on the line 2—2 of Fig. 1; and

Fig. 3 is a top plan view of a modified form.

Similar numerals refer to similar parts throughout the several figures.

Referring to the drawings, the piano plate 4 of suitable metal has the upper portion 5 and lower portion 6 providing the open space 7 therebetween, the outer ends being con-

nected by the support 8. Preferably such parts are integrally formed of cast metal. Such piano plate 4 is also provided with holes 9 along its outer margin through which pass screw bolts (not shown) to secure the plate 4 to the frame of the piano.

The sound-board 10 of the usual construction is disposed beneath, and in parallelism with, the piano plate 4 as shown in Fig. 2. Such sound-board 10 also has the openings 11 and 12 through which project downwardly the screw-threaded sockets 13 and 14 respectively of the piano plate 4. The brace bar 15 of Figs. 1 and 2 lies beneath the sound-board 10 and is rigidly secured to the piano plate 4 by the threaded screw-bolts 16 and 17 passing through washers 18 and 19 and then rigidly fastened in the threaded sockets 13 and 14 respectively.

The piano strings 20 are stretched taut between the pins 21 and tuning pins 22 affixed in the usual wrest-plank (not shown); the strings 20 pass over the bridge 23 affixed to the sound-board 10 with the strings 20 equally spaced-apart throughout the length of the bridge, and the two upper mute bars 24 beneath the pressure bar 25 the upper portion 5 of the piano plate 4 bearing on the sound-board 10 through the projection 26, all as shown in Fig. 2.

In the Fig. 3 construction I have shown the form of piano plate structure having the bass strings cross the treble strings with the X-shaped brace bars 27 bolted at 28 and 29 to the upper portion 5 and at 30 and 31 to the lower portion 6, while beneath the treble strings the short bar 32 is bolted at 33 and 34 to the opposite portions of the piano plate 4 to maintain the rigid construction for the two opposite-portions of the piano plate 4, yet the bridge 35 for the bass strings and bridge 36 for the treble strings have no disadvantageous gaps or breaks on account of the superposed arrangement of the brace bars 27, 28 and 32, since such brace bars lie beneath the sound-board 10 although these bars afford the necessary bracing for the piano plate 4 as hereinbefore explained in connection with the structure shown in Figs. 1 and 2.

Various changes may be made in the constructions shown without departing from the principle and scope of the claimed invention, the foregoing showing certain preferred embodiments of my invention.

I claim as my invention:

1. In a piano having strings, a piano plate and subjacent sound-board construction, and means for bracing the plate entirely beneath the sound board except at the margins of the plate beyond said strings.
2. In a piano having strings, a piano plate and subjacent sound-board construction, and a cross-bar for bracing the plate entirely beneath the sound board except at the margins of the plate beyond said strings.
3. In a piano having strings, a piano plate and subjacent sound-board construction, and a plurality of cross-bars for bracing the plate entirely beneath the sound board except at the margins of the plate beyond said strings.
4. In a piano, a piano plate and subjacent sound-board construction comprising a bridge mounted on the top surface of the sound-board and equally spaced-apart piano strings extending over the length of the bridge, and means for bracing the plate entirely beneath the sound-board except at the margins of the plate beyond said strings.
5. In a piano, a piano plate and subjacent sound-board construction comprising a bridge mounted on the top surface of the sound-board and equally spaced-apart piano strings extending over the length of the bridge, and a cross-bar arranged in substantial parallelism with said strings for bracing the plate entirely beneath the sound-board except at the margins of the plate beyond said strings and without breaking the uniform spacings of said piano strings.
